MECHANISM FOR FEEDING YARN IN CIRCULAR WEFT KNITTING MACHINES

Arthur Shortland, Leicester, England, assignor to
 Mellor Bromley & Co. Limited, Leicester, England, a British company

Application December 14, 1945, Serial No. 635,026
 In Great Britain December 19, 1944

19 Claims. (Cl. 66—134)

1

This invention relates to mechanism for feeding yarn to the needles of circular weft knitting machines of the type furnished with independent needles and sinkers or web holders, the expression "yarn" being used generically as including yarns or threads of any kind which may be used for the purpose intended.

The invention comprises improved yarn feeding mechanism for application to circular knitting machines of the type aforesaid with inside sinkers or web holders with the object of achieving certain advantageous results not only as regards introduction and withdrawal of a yarn at definite needles but also when a plurality of yarns are supplied together as in splicing and plating, or interchangeably as in the production of striping effects.

The invention is intended for application primarily to circular knitting machines with double axially opposed, e. g. superimposed, needle cylinders and double-ended needles operable by means of sliders, and inside holding-down sinkers or web holders.

The improved mechanism may be adapted to supply simply a single yarn for as long as may be required, or to supply a yarn in addition to, or instead of, a main yarn, as, for example, to produce spliced or plated areas, or reinforced areas, or/and elastic areas (by means of a rubber yarn), or to increase the rate of production of knitted fabric, or/and to supply a plurality of contrasting, e. g. differently coloured, yarns interchangeably for producing striping or analogous effects in knitted fabric or articles, according to requirements.

The yarn feeding mechanism according to the invention comprises, in its simplest form, a movable yarn guide and an associated yarn trapper, and is adapted to operate so that a length of a yarn held between the guide and the trapper is initially positioned so as to extend from front to back of a circular series of sinkers or web holders suchwise as to be engaged by a沉器 or web holder to effect introduction of the yarn to the needles. The mechanism is, of course, adapted to discontinue feeding a yarn to the needles, by reversion to its original position, during which movement the running yarn is trapped and severed so that another length is held in readiness for the next introduction.

A constructional form of the improved yarn feeding mechanism applicable to a circular knitting machine of the superimposed rotary needle cylinder type equipped with inside holding-down sinkers or web holders will now be described, by

2

way of example, with reference to the accompanying drawings, wherein

5 Figure 1 is a side view of the said yarn feeding mechanism, including the timing gear provided for timing the movements of the yarn guide and also controlling the operation of the trapper in relation to these movements,

10 Figure 2 is a further view of the said mechanism and timing gear as seen in the direction of the arrow A in Figure 1 and with the gear casing shown in section,

15 Figure 3 illustrates one form of the means employed for operating and controlling the yarn feeding mechanism,

20 Figure 4 is a detail view similar to the lower portion of Figure 3 depicting an alternative form of operating cam,

Figure 5 is a detail plan view of a portion of the沉器 ring or brass of the machine, showing the holding-down sinkers or web holders projected radially—with one of them projecting further than the remainder for the purpose hereinbefore mentioned,

25 Figure 6 is a detail perspective view of the same,

Figure 7 is a transverse sectional view taken on the line VII—VII of Figure 5 including also the associated沉器 cam rings,

30 Figure 8 is a developed view of so much of the knitting cam system of the machine, shown in relation to a few of the needles and sinkers or web holders, as is necessary to an understanding of the invention,

35 Figure 9 is a side view of the yarn guide and the trapper shown in relation to a needle and a沉器 and with the yarn cut and trapped prior to being presented to a沉器 or web holder,

Figure 10 is a corresponding detail transverse sectional view of the yarn guide and the trapper as seen from outside the needle cylinders, and

40 Figures 11 and 12, 13 and 14, 15 and 16 are views respectively similar to Figures 9 and 10 showing successive stages in the operation of the mechanism as will be hereinafter described.

45 Like parts are designated by similar reference characters throughout the drawings.

In the drawings the needles of the machine are indicated at 1 and the co-operating inside holding-down sinkers or web holders at 2.

50 The yarn feeding attachment shown in Figures 1 and 2 comprises a yarn guide 3 slidably mounted in a swivel 4 carried by a bracket 5 attached to the underside of the top plate 6 of the machine, with the guide 3 connected to a pin 7 in a crank 8, and a trapper T with a fixed jaw

9 and movable jaw 10. The trapper, which is also formed as a cutter, is fixed on the bracket 5 by means of screws 11. The jaws of the trapper T are of blade-like form and yieldingly held together by a compression spring 12 (Figure 2) suitably arranged. The operative end of the fixed jaw 9 is recessed at 9a to receive a yarn when withdrawn from knitting.

The bracket 5 is in the form of a casing, complete with cover 5a, adapted to house timing gear for operating the crank 8 and the movable jaw 10 of the trapper T. This gear includes a set of rotary timing cams mounted upon an axle 13 and adapted to be turned as the result of rotation in the appropriate direction of a pinion 14 through the medium of ratchet teeth such as 14a of a clutch device (see Figure 2). The said pinion, which is suitably spring controlled and mounted on a spindle 141, is arranged in mesh with a vertically disposed toothed rod or rack 15. This rod is slidably arranged within a tubular extension 5b of the casing 5 in which it is guided by a pin 16 working in a slot 17 formed in the wall of the said extension.

Secured to the axle 13 is a so-called feeder cam 18 for swinging the operative end of the yarn guide 3 downwards at appropriate times. A feeder "counter" cam 19 for moving the yarn guide in the reverse direction is attached to the side of the feeder cam 18. Suitably associated with the cam 18 so as to rotate therewith is a trapper cam 20 for moving the jaw 10 of the trapper suchwise as to sever and trap a yarn. For moving the jaw 10 in the reverse direction to open the trapper, a "counter" trapper cam portion 21 is attached by means of screws to the outer side of the cam 20. If desired, and as shown in Figure 1, the trapper cam 20, together with the attached countercam portion 21, may be made adjustable angularly with respect to the feeder cam 18, for which purpose the said trapper cam is formed with arcuate slots 20a through which are passed small set screws 22. In any event, the crank 8 is provided on the outer end of a spindle 23 to which is secured a pinion 24 (see Figure 2) arranged in mesh with a toothed quadrant 25. As will be seen more clearly in Figure 1, the quadrant 25 is constituted by an integral extension of a lever 26 which is pivoted at 27 and adapted to be actuated by the cams 18 and 19. For this purpose there is attached to the inner side of the said lever, at one side of the pivot 27, a nose-like element 28 arranged for contact with the feeder cam 18 whilst the free end 26a of the lever at the opposite side of the pivot is shaped somewhat similarly to the element 28 for contact with the feeder counter cam 19. For actuating the movable jaw 10 of the trapper T there is provided another lever 29 which is pivoted at 30 (Figure 1) and formed at 29a for engagement with the tail end of the movable jaw. This trapper-actuating lever 29 is formed with arms 29b and 29c disposed in different planes and at opposite sides of the pivot 30 for contact with the trapper cam 20 and the countertrapper cam 21 respectively. The construction so far described is therefore such that by depressing the toothed rod 15 the timing cams are turned for a partial revolution (preferably through 180° or thereabouts) as a consequence of which the yarn guide 3 is swung up and down as well as being alternately advanced and retracted radially, while the trapper is opened and closed. Whenever the rod 15 is raised the timing cams remain stationary by reason of the action of the saw clutch teeth 14a on the pinion 14. Thus, the yarn

guide and the movable trapper jaw are actuated in appropriate timed relation from the timing gear which is in turn adapted to be controlled from a cam rotating either in unison with or in suitable timed relation with respect to, the rotary needle cylinders 31 and 32 of the machine.

Thus, in the particular control arrangement depicted in Figure 3, the upper end of the toothed rod 15 projects up through the top of the gear casing 5 and is forked at 15a for connection to the outer end of a pivoted operating lever 33. This lever is connected by means of a link or rod 34 with a control lever 35 arranged with its operative end in contact with a rotary control cam 36.

Figure 4 illustrates an alternative form of control cam 36 secured upon a horizontally disposed ring 37 adapted to be racked as desired.

The mechanism is applied to the machine suchwise that normally the eye or throat 3a of the guide 3 and the jaws 9 and 10 of the trapper T are located above the nibs 2a of the holding-down sinkers or web holders 2, where the latter are projected, as shown in Figures 9 and 10, with the guide withdrawn so that the eye or throat 3a is further away radially from the sinkers or web holders than the jaws of the trapper. Thus when the guide 3 is threaded with a yarn y and the leading end of the yarn is engaged with the trapper T, a short length y¹ of the yarn extends outwards from the sinkers or web holders 2, horizontally, or substantially so, above the nibs 2a thereof. When the timing gear is operated to initiate feeding of the yarn y to the needles 1, the operative end 3a of the guide 3 is first swung downwards from its position above the sinkers or web holders 2 to a position below them thereby increasing the length of yarn between it and the trapper and disposing this length vertically, or substantially so, as indicated at y² in Figures 11 and 12, for engagement with the next following sinker or web holder 2¹ and introduction of the yarn to the needles descending at the yarn feeding location, then the guide 3 is swung upwards so that its eye or throat 3a is located above the sinkers or web holders 2, and somewhat above the trapper T to continue feeding the yarn to the needles as shown in Figures 13 and 14. When the yarn is taken by the needles it may be pulled out of the trapper or the latter may be opened by the timing gear to release the yarn. To discontinue feeding the yarn y, the timing gear is operated so as to withdraw the guide 3 radially from the sinkers or web holders 2 and lower it somewhat so that the yarn is located between the then open jaws of the trapper T (Figures 15 and 16) whereupon the trapper is operated to sever and trap the yarn (see Figure 9).

By reason of the circular movement of the sinkers or web holders 2 in relation to the yarn guide 3 the length y² of yarn engaged by a sinker or web holder 2¹ as aforesaid is folded or looped, and the upper portion of the fold or loop between the sinker or web holder and the trapper is ultimately engaged by the needle following the sinker or web holder while the lower portion of the fold or loop extends below the nibs of the following sinkers or web holders back to the guide until the latter is swung upwards and the yarn leaves the trapper, whereafter the yarn extends directly from the guide to the needles. A feeder plate 38, with a yarn receiving notch 38a therein, is provided between the yarn feeding mechanism and the needles 1 so that the feeding yarn is located in the notch when the guide occupies the feeding position shown in Figures 13 and 14.

The length y^2 of yarn held between the guide 3 and the trapper T (Figure 11) can properly be said to extend from front to back of the sinkers or web holders, since by the "front" of a sinker of this character is usually meant the uppermost or outermost edge thereof defining the nib 2a, the throat and the belly, whereas the "back" means the opposed underside or inner edge of the sinker.

The proximity of the guide 3 and the trapper T to the sinkers or web holders 2 may be such that when the guide is swung downwards the length of yarn y^2 is located between two normally projected sinkers or web holders, but if desired for further certainty of action, a sinker or web holder differentiated from the others, may be substituted for one of the ordinary sinkers, or a sinker modified as regards its butt formation may be provided and the sinker cam system may be modified so that this particular sinker projects further than the remainder when moved outwards, so that the position of the guide and trapper need not be so critical. Thus in the specific example illustrated, the particular sinker or web holder 2¹ which engages the length y^2 of yarn is differentiated from the others so as to project further than the remainder as shown clearly in Figures 5, 6 and 7. In these figures the sinker ring which is of conventional form, is indicated at 39 whilst in Figure 1 are also shown the associated upper and lower sinker cam rings 40 and 41 respectively.

In Figure 8 are depicted in diagrammatic fashion a few of the needles 1 and the sinkers or web holders 2 in the region of the knitting location KL. The knitting butts of the needle actuating sliders are indicated at 42, and at 43 is shown the stitch cam for forward knitting in the direction of the arrow B. The line SR represents the top of the sinker ring, and, for clarity, the operative ends of sinkers or web holders 2 are laid out flat in the plane of the needles, i. e. at right angles to the plane in which they are actually located. As is customary, the wave SW of outwardly projected sinkers or web holders 2 is in advance of the needle wave NW; the specially projected sinker 2¹ is shown at the centre of the wave SW. Where, as in the illustrated example the needles 1 are of the latch type, a slider such as that indicated at 44 with a butt 45 differing, e. g. longer than, the corresponding butts of the remaining sliders may be incorporated in the needle cylinder 31 for action thereupon by a cam 46 designed to effect a premature lowering of the corresponding needle 1¹ so that the portion of yarn extending between the specially projected sinker or web holder 2¹ and the trapper is located between the hook and the latch of the said needle further to ensure initial engagement of the yarn with the needle. If desired, two or more needles may be prematurely lowered in this way.

In the application of the invention to a circular knitting machine without sliders, the different butt or butts would be provided on the appropriate needles.

For yarn changing purposes two or more guides are provided, operable by appropriate timing gear in conjunction with individual trapping and severing units, or a common trapping and severing unit, and the guides are preferably formed so as to converge upon a common yarn feeding location, e. g. the notch in the aforesaid feeder plate.

The improved yarn feeding mechanism may be applied to circular knitting machines of the stationary needle cylinder type as well as to machines of the rotary needle cylinder type, and as will be understood, in the former case engage-

ment of an ingoing yarn with the needles will be effected by virtue of circular movement of the feeding mechanism in relation to the sinkers or web holders.

5 The invention may also be applied to circular knitting machines with bearded needles.

By appropriate timing the mechanism may be adapted to feed a yarn or yarns for partial courses as well as for complete courses of knitting.

10 It is considered that with the improved yarn feeding mechanism the appearance of loose ends and bulky joins in the fabric when yarns are supplied interchangeably or intermittently will be avoided as far as possible and that so far as plating and splicing are concerned clearly defined plated or spliced areas will be produced in the knitted fabric.

15 What I claim then is:

20 1. In a circular weft knitting machine, in combination, at least one needle cylinder, a set of independent needles for operation in said cylinder, a circular series of sinkers arranged to co-operate with the needles when knitting, and mechanism for feeding yarn to the needles, said mechanism comprising a movable yarn guide, an associated trapper, and means for operating the said guide and the trapper in timed relation suchwise that when the mechanism is rendered operative a length of yarn held between the guide and the trapper is initially positioned so as to extend from front to back of the sinkers and to be engaged by a sinker to effect introduction of the yarn to the needles.

25 2. In a circular weft knitting machine, in combination, at least one needle cylinder, a set of independent needles for operation in said cylinder, a circular series of sinkers arranged to co-operate with the needles when knitting, and mechanism for feeding yarn to the needles, said mechanism comprising a movable yarn guide, an associated trapper, and means for operating the said guide and the trapper in timed relation suchwise that when the mechanism is rendered operative a length of yarn held between the guide and the trapper is initially positioned so as to extend from front to back of the sinkers and to be engaged by a sinker to effect introduction of the yarn to the needles whereafter, to discontinue feeding the yarn to the needles the mechanism reverts to its original position, during which movement the running yarn is trapped and severed so that another length is held in readiness for the next introduction.

30 3. In a circular weft knitting machine, in combination, at least one needle cylinder, a set of independent needles for operation in said cylinder, a circular series of sinkers arranged to co-operate with the needles when knitting, a stitch cam for imparting stitch forming movements to the needles, means for actuating the sinkers and so timing them in relation to the said stitch forming movements that the sinkers are projected radially in advance of the stitch cam so that the needles draw loops over the projected sinkers, and beyond the stitch cam the sinkers are retracted to hold the newly formed stitches while the needles are cleared and mechanism for feeding yarn to the needles, said mechanism comprising a movable yarn guide, an associated trapper and

35 4. In a circular weft knitting machine, in combination, at least one needle cylinder, a set of independent needles for operation in said cylinder, a circular series of sinkers arranged to co-operate with the needles when knitting, a stitch cam for imparting stitch forming movements to the needles, means for actuating the sinkers and so timing them in relation to the said stitch forming movements that the sinkers are projected radially in advance of the stitch cam so that the needles draw loops over the projected sinkers, and beyond the stitch cam the sinkers are retracted to hold the newly formed stitches while the needles are cleared and mechanism for feeding yarn to the needles, said mechanism comprising a movable yarn guide, an associated trapper and means for operating the said guide and the trapper in timed relation suchwise that when the mechanism is rendered operative a length of yarn held between the guide and the trapper is initially positioned so as to extend from front to back of

the sinkers and to be caught by a projected sinker to effect introduction of the yarn to the needles.

4. In a circular weft knitting machine, in combination, at least one needle cylinder, a set of independent needles for operation in said cylinder, a circular series of sinkers arranged to co-operate with the needles when knitting, a stitch cam for imparting stitch forming movements to the needles, means for actuating the sinkers and so timing them in relation to the said stitch forming movements that the sinkers are projected radially in advance of the stitch cam so that the needles draw loops over the projected sinkers, and beyond the stitch cam the sinkers are retracted to hold the newly formed stitches while the needles are cleared, one of the sinkers being adapted, when projected, to project further than the remainder, and mechanism for feeding yarn to the needles, said mechanism comprising a movable yarn guide, an associated trapper, and means for operating the said guide and the trapper in timed relation suchwise that when the mechanism is rendered operative a length of yarn held between the guide and the trapper is initially positioned so as to extend from front to back of the sinkers and to be caught by the specially projected sinker to effect introduction of the yarn to the needles.

5. In a circular weft knitting machine, in combination, at least one needle cylinder, a set of independent needles for operation in said cylinder, a circular series of sinkers arranged to co-operate with the needles when knitting, a stitch cam for imparting stitch forming movements to the needles, means for actuating the sinkers and so timing them in relation to the said stitch forming movements that the sinkers are projected radially outwards in advance of the stitch cam so that the needles draw loops over the projected sinkers, and beyond the stitch cam the sinkers are retracted to hold the newly formed stitches while the needles are cleared, and mechanism for feeding yarn to the needles, said mechanism comprising a movable yarn guide, an associated trapper fixed in front of the series of sinkers, means for opening and closing the said trapper at appropriate times, and means for moving the yarn guide from front to back of the sinkers in the region of outward projection thereof, and vice versa, in timed relation with the operation of the trapper, the construction and arrangement of the said mechanism being such that when the yarn guide is moved to the back of the sinkers a length of yarn held between the said guide and the trapper is increased and presented to a projected sinker to effect introduction of the yarn to the needles.

6. In a circular weft knitting machine, in combination, at least one needle cylinder, a set of independent needles for operation in said cylinder, a circular series of sinkers arranged to co-operate with the needles when knitting, a stitch cam for imparting stitch forming movements to the needles, means for actuating the sinkers and so timing them in relation to the said stitch forming movements that the sinkers are projected radially outwards in advance of the stitch cam so that the needles draw loops over the projected sinkers, and beyond the stitch cam the sinkers are retracted to hold the newly formed stitches while the needles are cleared, and mechanism for feeding yarn to the needles, said mechanism comprising a movable yarn guide, an associated trapper fixed in front of the series of sinkers, means for opening and closing the said trapper

at appropriate times, and means for moving the yarn guide from front to back of the sinkers in the region of outward projection thereof, and vice versa, in timed relation with the operation of the trapper, the construction and arrangement of the said mechanism being such that when the yarn guide is moved to the back of the sinkers a length of yarn held between the said guide and the trapper is increased and presented to a projected sinker to effect introduction of the yarn to the needles, whereafter the yarn guide reverts to a position in front of the sinkers to continue feeding the yarn to the needles.

7. In a circular weft knitting machine, in combination, at least one needle cylinder, a set of independent needles for operation in said cylinder, a circular series of sinkers arranged to co-operate with the needles when knitting, a stitch cam for imparting stitch forming movements to the needles, means for actuating the sinkers and so timing them in relation to the said stitch forming movements that the sinkers are projected radially outwards in advance of the stitch cam so that the needles draw loops over the projected sinkers, and beyond the stitch cam the sinkers are retracted to hold the newly formed stitches while the needles are cleared, and mechanism for feeding yarn to the needles, said mechanism comprising a movable yarn guide, an associated trapper fixed in front of the series of sinkers, means for opening and closing the said trapper at appropriate times, and means for moving the yarn guide from front to back of the sinkers in the region of outward projection thereof, and vice versa, in timed relation with the operation of the trapper, the construction and arrangement of the said mechanism being such that when the yarn guide is moved to the back of the sinkers a length of yarn held between the said guide and the trapper is increased and presented to a projected sinker to effect introduction of the yarn to the needles, and for withdrawing the yarn from the needles the yarn guide is retracted radially from the sinkers and the trapper is opened so that the yarn is located therein whereupon the trapper is closed and the yarn is severed.

8. In a circular weft knitting machine, in combination, at least one needle cylinder, a set of independent needles for operation in said cylinder, a circular series of sinkers arranged to co-operate with the needles when knitting, a stitch cam for imparting stitch forming movements to the needles, means for actuating the sinkers and so timing them in relation to the said stitch forming movements that the sinkers are projected radially outwards in advance of the stitch cam so that the needles draw loops over the projected sinkers, and beyond the stitch cam the sinkers are retracted to hold the newly formed stitches while the needles are cleared, and mechanism for feeding yarn to the needles, said mechanism comprising a movable yarn guide, an associated trapper fixed in front of the series of sinkers, means for opening and closing the said trapper at appropriate times, and means for moving the yarn guide from front to back of the sinkers in the region of outward projection thereof, and vice versa, in timed relation with the operation of the trapper, the construction and arrangement of the said mechanism being such that when the yarn guide is moved to the back of the sinkers a length of yarn held between the said guide and the trapper is increased and presented to a projected sinker to effect introduction of the yarn to the needles, whereafter the yarn guide reverts to a

position in front of the sinkers to continue feeding the yarn to the needles, and for withdrawing the yarn from the needles the yarn guide is retracted radially from the sinkers and the trapper is opened so that the yarn is located therein whereupon the trapper is closed and the yarn is severed.

9. A combination according to claim 2, wherein the trapper is formed with cutting edges so that severance of the yarn is effected by the closing of the trapper.

10. In a circular weft knitting machine, in combination, at least one needle cylinder, a set of independent needles for operation in said cylinder, a circular series of sinkers arranged to co-operate with the needles when knitting, a stitch cam for imparting stitch forming movements to the needles, means for actuating the sinkers and so timing them in relation to the said stitch forming movements that the sinkers are projected radially outwards in advance of the stitch cam so that the needles draw loops over the projected sinkers, and beyond the stitch cam the sinkers are retracted to hold the newly formed stitches while the needles are cleared, and mechanism for feeding yarn to the needles, said mechanism comprising a yarn guide pivotally and slidably arranged in relation to a trapper fixed in front of the series of sinkers, means for opening and closing the said trapper at appropriate times, and means for actuating the yarn guide so that its operative end describes an arc in moving from front to back of the sinkers in the region of outward projection thereof, and vice versa, in timed relation with the operation of the trapper, the construction and arrangement of the said mechanism being such that when the yarn guide is moved to the back of the sinkers a length of yarn held between the said guide and the trapper is increased and presented to a projected sinker to effect introduction of the yarn to the needles, and for withdrawing the yarn from the needles the yarn guide is retracted linearly from the sinkers and the trapper is opened so that the yarn is located therein whereupon the trapper is closed and the yarn is severed.

11. In a circular weft knitting machine, in combination, at least one needle cylinder, a set of independent needles for operation in said cylinder, a circular series of sinkers arranged to co-operate with the needles when knitting, and mechanism for feeding yarn to the needles, said mechanism comprising a movable yarn guide, an associated trapper and cam and crank means for operating the said guide and the trapper in timed relation suchwise that when the mechanism is rendered operative a length of yarn held between the guide and the trapper is initially positioned so as to extend from front to back of the sinkers and to be engaged by a sinker to effect introduction of the yarn to the needles.

12. In a circular weft knitting machine, in combination, at least one rotary needle cylinder, a set of independent needles for operation in said cylinder, a circular series of inside holding-down sinkers arranged to co-operate with the needles when knitting, and mechanism for feeding yarn to the needles, said mechanism comprising a bracket, a swivel carried by said bracket, a yarn guide slidably mounted in the swivel, a crank furnished with a pin to which the said guide is connected, a trapper having a fixed jaw and a movable jaw and also formed as a cutter fixed on the aforesaid bracket, timing gear for operating the crank and the movable jaw of the trapper in suitable

timed relation, and driven means for controlling the said timing gear suchwise that when the mechanism is rendered operative a length of yarn held between the guide and the trapper is initially positioned so as to extend from front to back of the sinkers and to be engaged by a sinker to effect introduction of the yarn to the needles.

13. In a circular weft knitting machine, in combination, at least one rotary needle cylinder, a set of independent needles for operation in said cylinder, a circular series of inside holding-down sinkers arranged to co-operate with the needles when knitting, a stitch cam for imparting stitch forming movements to the needles, means for actuating the sinkers and so timing them in relation to the said stitch forming movements that the sinkers are projected radially in advance of the stitch cam so that the needles draw loops over the projected sinkers, and beyond the stitch cam the sinkers are retracted to hold the newly formed stitches while the needles are cleared, the mechanism being applied to the machine suchwise that normally the eye of the yarn guide and the jaws of the trapper are located above the nibs of the holding-down sinkers, where the latter are projected; with the guide withdrawn so that the eye is further away radially from the sinkers than the jaws of the trapper whereby when the guide is threaded with a yarn and the leading end of the yarn is engaged with the trapper, a short length of the yarn extends outwards from the sinkers, substantially horizontally, above the nibs thereof, whereby when the timing gear is operated to initiate feeding of the yarn to the needles the operative end of the guide is first swung downwards from its position above the sinkers to a position below them, thereby increasing the length of yarn between it and the trapper and disposing this length substantially vertically for engagement with a projected sinker and consequent introduction of the yarn to the needles descending at the yarn feeding location, then the yarn guide is swung upwards so that its eye is located above the sinkers and somewhat above the trapper to continue feeding the yarn to the needles.

14. In a circular weft knitting machine, in combination, at least one rotary needle cylinder, a set of independent needles for operation in said cylinder, a circular series of inside holding-down sinkers arranged to co-operate with the needles when knitting, a stitch cam for imparting stitch forming movements to the needles, means for actuating the sinkers and so timing them in relation to the said stitch forming movements that the sinkers are projected radially in advance of the stitch cam so that the needles draw loops over the projected sinkers, and beyond the stitch cam the sinkers are retracted to hold the newly formed stitches while the needles are cleared, the mechanism being applied to the machine suchwise that normally the eye of the yarn guide and the jaws of the trapper are located above the nibs of the holding-down sinkers, where the latter are projected, with the guide withdrawn so that the eye is further away radially from the sinkers than the jaws of the trapper whereby when the guide is threaded with a yarn and the leading end of the yarn is engaged with the trapper, a short length of the yarn extends outwards from the sinkers, substantially horizontally, above the nibs thereof, whereby when the timing gear is operated to initiate feeding of the yarn to the needles the operative end of the guide is first swung downwards from its position above the sinkers to

a position below them, thereby increasing the length of yarn between it and the trapper and disposing this length substantially vertically for engagement with a projected sinker and consequent introduction of the yarn to the needles descending at the yarn feeding location, then the yarn guide is swung upwards so that its eye is located above the sinkers and somewhat above the trapper to continue feeding the yarn to the needles, whereafter to discontinue feeding the yarn the timing gear is operated so as to withdraw the guide radially from the sinkers and lower it so that the yarn is located between the then open jaws of the trapper after which the latter is operated to sever and trap the yarn.

15. In a circular weft knitting machine, in combination, at least one needle cylinder, a set of independent latch needles for operation in said cylinder, a circular series of sinkers arranged to co-operate with the needles when knitting, a stitch cam for imparting stitch forming movements to the needles, means for actuating the sinkers and so timing them in relation to the said stitch forming movements that the sinkers are projected radially in advance of the stitch cam so that the needles draw loops over the projected sinkers, and beyond the stitch cam the sinkers are retracted to hold the newly formed stitches while the needles are cleared and mechanism for feeding yarn to the needles, said mechanism comprising a movable yarn guide, an associated trapper, means for operating the said guide and the trapper in timed relation suchwise that when the mechanism is rendered operative a length of yarn held between the guide and the trapper is initially positioned so as to extend from front to back of the sinkers and to be caught by a projected sinker to effect introduction of the yarn to the needles, and a cam for prematurely lowering at least one needle at the yarn feeding location so that the portion of yarn extending between the engaging sinker and the trapper is located between the hook and the latch of the said needle further to ensure initial engagement of the yarn with the needles.

16. For application to a circular weft knitting machine, a yarn feeding attachment comprising, in combination, a bracket, a swivel carried by said bracket, a yarn guide slidably mounted in the swivel, a crank furnished with a pin to which the said guide is connected, a trapper fixed to said bracket, said trapper having a fixed jaw and a movable jaw and being also formed as a cutter, and timing gear for operating the crank and the movable trapper jaw in suitable timed relation.

17. For application to a circular weft knitting machine, a yarn feeding attachment comprising, in combination, a bracket, a swivel carried by said bracket, a yarn guide slidably mounted in

the swivel, a crank furnished with a pin to which the said guide is connected, a trapper fixed to said bracket, said trapper having a fixed jaw and a movable jaw and being also formed as a cutter, rotary cams for actuating the yarn guide by swinging it first in one direction and then in the other, associated rotary cams for moving the aforesaid movable jaw back and forth to open and close the trapper in timed relation with the movements of the yarn guide, connections through which the rotary timing cams are adapted to be controlled, and levers actuated by the said cams for transmitting the required movements to the crank and the movable trapper jaw respectively.

18. For application to a circular weft knitting machine, a yarn feeding attachment comprising, in combination, a bracket, a swivel carried by said bracket, a yarn guide slidably mounted in the swivel, a crank furnished with a pin to which the said guide is connected, a trapper fixed to said bracket, said trapper having a fixed jaw and a movable jaw and being also formed as a cutter, a set of rotary cams for timing the movements of the yarn guide and the movable trapper jaw, rack and pinion gear through which the angular movements of the timing cams are adapted to be controlled, a pinion connected with the aforesaid crank, a pivoted lever adapted to be actuated by the appropriate timing cams and formed with a toothed quadrant arranged in mesh with the said pinion, and a further pivoted lever which is engaged with the movable trapper jaw and adapted to be actuated by the remaining timing cams.

19. For application to a circular weft knitting machine, a yarn feeding attachment comprising, in combination, a bracket, a yarn guide pivotally and slidably arranged on said bracket, a trapper fixed to said bracket, said trapper having a fixed jaw and a movable jaw and being also formed as a cutter, timing gear for operating the yarn guide and the movable trapper jaw in suitable timed relation, and means for controlling the operation of the timing gear according to requirements.

ARTHUR SHORTLAND.
